ELECTROAUTOMATIC DOCUMENT
COLLECTOR AND DISTRIBUTOR

William C. Gibson, O'Bannon, Ky.

Application March 18, 1940, Serial No. 324,737

2 Claims. (Cl. 186—7)

My invention relates to devices that may be made to operate electrically on an endless railway suspended from the office ceiling or from any desirable special structure therefor, not interfering with the normal traffic of the office and adapted in combination with coacting appurtenances electrically operative, to collect and distribute various documents from and to a central station and from and to other designated, individual stations along the course of said railway. And the principal object of my instant invention has been the designing and development of an electrically operative composite mechanism, adapted to work together in the collection and distribution of office documents to save time and expense in the transfer of said papers between several designated stations in one room. Other detail objects of my invention will be disclosed timely in the process of this specification.

The foregoing object has been efficiently attained in my present invention; and my new and useful electro-automatic document-collector-and-distributor for offices and sales-rooms, illustrated in the accompanying drawings forming a part of this specification, is a practical device embodying the aforesaid novel means and other new and useful details of construction, arrangement and combination of parts, all of which together with their functions, will be described in detail with reference to said drawings and will be definitely pointed out in the claims that follow this description, so that any person skilled in the art may be able to construct and use this invention.

In said drawings,

Fig. 1 is a plan view, in vertical projection, of the endless railway on which the document-conveyor cars are electrically operated, showing three document-conveyors thereon and some of the individual stations at desks along the railway line.

Fig. 2 is a side elevational view of a part of the endless railway and the electric trolley system, showing the flexible wooden band on which the flat trolley wires are mounted, also the ceiling line and the long steel cable attached thereto, as well as the short suspension wires for supporting the railway, its cars and trolley system. In this Fig. 2, also, are shown two individual stations at desks and a document-conveyor installed in its operative position on the rail.

Fig. 3 is a side elevational view of my document-conveyor car and a fragment of the rail on the underside of which the car runs. In this Fig. 3 are shown the operative electric motor of

the car, and its driving and bracing wheels and carbon brushes and the pick-up and distributing channels installed under the car.

Fig. 4 is an elevational view of the front end of the conveyor-car, showing the worm-gear between the two driving wheels, the four idle bracing wheels, the post carrying the carbon brushes and the three pick-up and distributing channels installed on a plate under the car. In this Fig. 4, also, is shown a cross-section of the wooden band on which the trolley wires are installed.

Fig. 5 is a side elevational view in detail of one of the carbon brushes that ride continuously on the flat trolley wires; the casing thereof being sectioned to show the brush and the spring pressing it.

Fig. 6 is an elevational view of one of the individual stations along the railway line, showing the attendant's desk, the elevator-post, the pick-off channels, the elevating motor and its supporting post with a pair of coacting solenoids and a two-way switch for controlling the motor.

Fig. 7 is a plan view in vertical projection of one of the pick-off and release channels open, to be mounted on the elevator arm shown in Figs. 6 and 9.

Fig. 8 is a side elevation of the pick-off and release channel shown in Fig. 7. Fig. 9 is a side view in detail of a portion of the elevator-post, partly in elevation; the casing being sectioned to show the threaded elevator-rod and the threaded clamp and its horizontal arm and its pick-off and release channel which move up and down as the threaded elevator-rod is turned.

Fig. 10 is a plan view of the pick-off and release channels installed on a plate fixed on the bottom of each car; showing the bottom of the channels, the pick-off slot and the spring-pressed release latches pivoted in the bottoms of the channels. Fig. 11 is a detail view in elevation of the front of a fragment of the lower portion of the elevator post, showing the spring-pressed lower-limit switch open, stopping the elevator-motor.

Fig. 12 is a detail view in elevation of a short section of the endless railway showing the rail and its vertical flange and the flexible wooden band, the flat trolley wires installed thereon and the brush-post of the conveyor-car with the brushes thereon, and metal supporting strip for railway parts.

Fig. 13 is a detail view of a cross-section of the parts shown in Fig. 12.

Fig. 14 is a detail view of an electrically-oper-

ative device with a pair of coating solenoids and a connected two-way switch.

Fig. 15 is an elevational view of the back of one type of a document-holder, showing the pick-off dowels set in the upper portion thereof.

Fig. 16 is an elevational view of the side of the document-holder shown in Fig. 15, showing the spring-pressed clip for holding documents in transit.

Fig. 17 is an elevational view of the back of another type of document-holder, showing the spring-clip for hanging on the pick-off channel. Fig. 18 is an elevational view of the side of the holder shown in Fig. 17, showing near the lower end thereof, the spring-pressed clip for holding documents in transit.

Fig. 19 is a diagrammatic representation of the electric circuits involved in the automatic operation of the elevator mechanism of Fig. 6.

This invention has been designed and experimentally developed in its details of construction for the purpose of producing at a minimum of cost a durable, useful and efficient electro-automatic document-collector-and-distributor for general use in large offices and sales-rooms and in other apartments where it would be convenient for letters and papers to be automatically collected and distributed. And with said purpose and the special objects aforesaid in view, I will now describe my invention more fully in detail, pointing out the new and useful features of the construction and the operation of the individual parts and the combination thereof, as illustrated in the drawings hereinabove described, in which similar letters and characters refer to similar parts throughout the several views.

In the invention and development of my new electro-automatic document-collector-and-distributor, for the sake of economy in production and efficiency in operation, I have designed an endless railway $\mathfrak{t}$ as shown in Fig. 1 and having one rail suspended from the room-ceiling or from any desirable special structure therefor as shown in Fig. 2, and, not interfering with the normal traffic of the office and, in combination with other coating appurtenances electrically operative, adapted to collect and distribute automatically various documents and small packages from and to a terminal station and from and to other designated, individual stations along the course of said railway. For operation on said railway, in combination therewith, I have designed and constructed a plurality of document-conveyors, $2a$, $2b$, $2c$, shown in Fig. 1, and all operative in the same direction from an electric trolley system rigidly mounted on said railway and getting its current from the supply wires $1h$, $1h$, shown in Fig. 1.

Document-conveyor cars

The document-conveyor cars, $2a$, $2b$ and $2c$, that I have designed for service in my equipment for automatically collecting and distributing documents from and to the different stations on my railway line, all have the same size, construction and appurtenances. Each one, as shown in Figs. 3 and 4, is equipped with a small electric motor 5 for operating the car provided with a worm and its worm-gear $5a$ mounted on the driving shaft $5b$. And mounted on this shaft $5b$ are two metal driving wheels, $5c$, $5c$, provided with rubber tires which contact the under side of the flat bottom of the rail 7 , which is an inverted T as shown in cross-section in Fig. 13.

To ensure a firm contact between the rail 7

and the driving wheels, $5c$, $5c$, I have installed on rigid brackets in the car a pair of idle bracing wheels, $5d$, $5d$, provided with rubber tires and adapted to ride on the upper side of the horizontal flanges of the rail 7 . And, also, for bracing against the side-movement of the car along the rail 7 , I installed on rigid brackets in the car a pair of idle rubber-tired horizontal wheels, $5x$, $5x$, designed to ride on each side of the vertical flange of said rail. For electric current to operate the car I have installed in a predetermined place in the car a rigid post 6 on the upper portion of which I have mounted five spring-pressed, carbon brushes, $6a$, $6b$, $6c$, $6d$, $6x$, extending out horizontally from the brush-post 6 to the wooden band 4 on which the trolley wires, $4a$ and $4b$ are installed, as shown in Figs. 2 and 12. The brushes, $6a$ and $6b$, ride along continuously in contact respectively with the upper and the lower trolley wires; said brushes being connected with the wires $6y$ and $6z$ running down the post 6 to the motor of the car, as shown in Fig. 3, but the other brushes, $6c$, $6d$ and $6x$ make contact intermittently with tappet-switches $4y$, $4y$, $4y$ and $4y'$, $4y'$, $4y'$ installed on the wooden band 4 along the railway line for certain purposes which I will soon describe under the individual head of elevator mechanism. Said trolley system is energized from an adjacent electric source through the supply wires $1h$, $1h$, shown in Fig. 1.

Every document-conveyor car is equipped with three or more similar pick-off and release channels 8 , 8 , fixed longitudinally, a predetermined distance apart, on the under side of a plate fastened to the bottom of the car. The front ends of these channels have broad, beveled openings to allow the document-holders, 9 , $9'$, shown in Figs. 16 and 18 respectively to pass readily into slots of the channels. And on each one of these pick-off and release channels, I have designed a spring-pressed latch $8a$ operative on a pintle-hinge on the bottom of the channel and reaching across the slot of the channel and adapted to prevent any document-holders that have entered the channel-slot, from passing therethrough until a station is reached where said document-holders are intended to be automatically released. And for such stations I have provided the means for releasing them, a tappet-plate $11b$ fixed on arm 11 .

The exact manner in which the channels, 8 , 8 , support a document-holder, 9 , $9'$ may be more clearly understood from the following: The attendant at any of the individual way-stations or at the terminal station on the railway line, first clasps the documents that he desires to send away in the spring-clip of the holder 9 or $9'$; and then hangs the holder 9 in his pick-off-and-release channel mounted on the arm 11 at his station. He places the holder 9 between the wings $11a$ and $11c$ of his channel so that the opposite ends of the lower rectangular dowel-pin of the holder 9 shown in Fig. 15, rest on the wings $11a$ and $11c$ of his channel, to be picked off by one of the pick-off-and-release channels of the on-coming car. If the station attendant uses document-holder $9'$ he will, by means of the side spring-clip $9'a$, hang the holder on the inside of wing $11c$, so that the holder $9'$ will hang in the long channel-slot between the wings, $11a$ and $11c$ with the top dowel-pin $9'b$ extending across the slot in his station-channel so that said dowel-pin will be caught on the wings of one of the pick-off-and-release channels of the on-coming car. When the car-channel is passing his station, the

shank of the holder 9 or 9' slips automatically between the wings of the car-channel; and as the shank of the holder is too wide to turn between the wings of the car-channel the dowel-pin across its top rests on the wings of said channel and slides back on the wings of the channel; and the shank of the holder strikes against the spring-pressed latch 8a, fixed across the car-channel 8, and rides along with the car. If other document-holders are picked off from other stations along the line by this same car-channel, they will slide back against the first ones, and all will be released at the designated station where a baffle plate 11b is fixed to intercept the spring-pressed latch on the car-channel carrying said document-holder. When the outer end of the spring-pressed latch 8a on the moving car, strikes the baffle plate 11b, the inner end of said latch swings forward clearing the slot in the car-channel so that the document-holders are released as they strike the wings of the station channel 11a and 11c, on which they ride down toward the desk 10 until released by the automatic action of arm 12 which forces the wing 11a of the station-channel to swing open so the document holders drop on the desk 10 of that station.

The elevator mechanism

To raise documents from an attendant's desk 10 to the passing cars overhead, I have designed a novel elevator automatically operated by means of a reversible electric motor 10a, and intermediate electrically-operative switches. The elevator is mounted on a supporting post fixed adjacent said desk, and consists of a vertically-disposed tubular casing 10b enclosing a threaded rod 10c installed in thrust ball-bearings at the top and at the bottom. The threaded rod 10c carries a threaded clamp 10d slotted to match and correspond with the threads on the rod 10c, so that, when said rod is turned one way the clamp 10d will move upward and when the rod is turned the opposite way, the clamp will move downward. This threaded clamp 10d extends out through a vertical slot 10z in the front side of said casing where it is rigidly attached to a vertically-disposed metal shank 10x longitudinally mortised at either end to receive a straight vertical bend of a horizontal arm 11. This metal shank 10x is designed to move up and down along the vertical slot in the casing 10b; and to prevent its fluctuation from side to side I have fastened an outstanding vertical rib 10m on each side of said slot. And on the horizontal arm 11 anchored in the vertical mortise of the shank 10x, I have mounted station pick-off and release channels 11a, 11a of the type shown in Figs. 6, 7 and 8, and tappet-plates 11b, 11b, to open the spring-pressed latches 8a, 8a on the pick-off and release channels, 8, 8, on the cars.

Line 4a connects with the solenoids 3a and 3b, line 4b on switch and armature #1 and line 4b on the opposite end of reversing switch 3c, thence through switch 3c to motor.

Lines 4a, 3 and 4 are of the same polarity and operate as follows: Car on mono-rail closes momentary tappet switch 4y' on line 3 for up-trip, and supplies current to motor until limit switch 10y at top is opened. After the car passes the station, it closes the momentary tappet switch 4y which puts the current in the solenoid 3b which causes the reversing switch 3c to reverse the motor for the down-trip and supplies current until the limit switch 10y at the top closes shunting the

current to the line 4a; and solenoid 3a places the reversing switch 3c in the proper position for another up-trip.

Now for the control of the reversible electric-motor 10a, I have designed the electrically-operative device 3 provided with a pair of coacting solenoids, 3a and 3b and a connected two-way switch 3c. This device 3 I have mounted on the supporting post adjacent the reversible motor 10a and connected up the solenoids in circuits from the tappet-switches set at certain raised places on the wooden band 4, and energized from the trolley wires. One of said tappet-switches would be placed at a predetermined distance before the car reached the station and the other one after the car had passed the station. The former would energize solenoid 3a which would energize the motor 10a to turn the threaded rod 10c to force the horizontal arm 11 and its station pick-off and release channel 11a up to meet the passing car to exchange documents. As the arm 11 reaches its maximum height on the elevator, it trips open a limit-switch 10y on the upper end of the elevator, cutting the current from the motor 10a. And after the car passes the station, its brush strikes another tappet-switch which energizes momentarily the other solenoid 3b which throws the two-way switch 3c to its other contact reversing the motor 10a turning the threaded rod 10c in opposite direction which forces the shank 10x and its horizontal arm 11 down again to the position shown in Fig. 6, and the lower limit-switch 10s has been forced open by the shank 10x, as shown in Fig. 11, to stop the elevator motor 10a; and the inner, hinged side of the station release channel 11a has been forced open by the arm 12a, allowing any document-holder that it may have picked off from the passing car to fall to the top of the desk 10. When the channel 11a was coming down from the passing car it was closed, as shown in Fig. 9; but as it reached the lowest place on the elevator it was then opened automatically by means of a spring-pressed lever 12 which I designed to be mounted on the side of shank 10x in a pintle-hinge. The little wheel 12b on the inner side of the lever rolls smoothly up and down on the outside of the elevator casing and the station pick-off channel remains closed as shown in Fig. 9 and the dowel pins in the upper ends of the document-holders, 9, 9', keep the holders from dropping through the station channels until the channels are nearly down to the attendant's desk when the small wheel 12b rolls up on a raised tappet 10t, as shown in Fig. 6, and the lever 12 is forced out and by means of its arm 12a forces the inner side of the channel open at the top far enough to allow the dowel pins of the document-holders to drop through; and the holders and documents therein drop to the desk. On the horizontal arm 11, I have fixed a baffle plate 11b designed to intercept the spring-pressed latches, 8a, 8a, hinged on the pick-off and release channels 8, 8, on the conveyor-cars, so that any documents collected or placed thereon may be left behind at any designated station.

Now the operative relationship of lever 12 and arm 12a to the post 10b and to the wing 11a of the station-channel may be more fully understood, when we notice the raised tappet strip fastened on the lower front portion of the post 10b and see that the lever 12 with its attached roller 12b is continuously pressed against the casing 10b by means of the torsion spring 12c, as shown in Figs. 6 and 9, and we notice that the channel-

wing $11a$ hinged on arm 11 in the pintle $11h$ is continuously held in its closed position by means of the torsion spring $11d$, as shown in Fig. 9; for the channel-wing $11a$ will remain closed until pushed open by means of the horizontal arm $12a$ attached in pintle-hinges to the upper end of lever 12 and to the lower end of the channel-wing $11a$. Now the roller $12b$ on the inner side of the spring-pressed lever 12 rolls smoothly up and down on the outside of the elevator-casing $10b$ allowing the station pick-off channel to remain closed, as shown in Fig. 9, while the dowel-pins in the upper ends of the document-holders $9, 9'$ keep the holders from dropping through the station-channels, but when the channel is almost down to the attendant's desk 10 , the wheel $12b$ rolls up on a raised tappet strip $10t$, as shown in Fig. 6, pushing the spring-pressed lever 12 out a little way from the casing $10b$, which forces the arm $12a$ and the lower end of channel-wing $11a$ outward sufficiently to swing open the upper part of said wing allowing the document holders therein to drop to the attendant's desk. The electrically-operative device 3 shown in Figs. 6 and 14 is composed of a square plate, as shown, and two solenoids rigidly mounted thereon in the positions as shown. And the plungers of said solenoids are hanging from pintle-hinges fixed at the opposite ends of a horizontal strip rigidly mounted across an upper segment of the rotary circular plate $3c$. On the backside of the circular plate $3c$ are mounted two switches, so set that when the solenoid $3a$ on the left is energized, the plunger of said solenoid strikes inwardly rotating the rotary plate $3c$ to the left, closing the switch on the left backside of plate $3c$ and opening the switch on the right backside of said plate. And when the solenoid $3b$ on the right is energized, its plunger strikes in and rotates the rotary plate to the right, closing the switch on the right backside of the rotary plate $3c$ and opening the switch on the left backside of said rotary plate.

Different cars for different stations on same line

Each of these document-conveyor cars, $2a, 2b$ and $2c$ may be selected and marked to collect and distribute documents between certain designated stations on the same line, passing all other stations without collecting or distributing documents. This process is accomplished in the following way: The cars on the line may be numbered and the stations on the line may also be numbered. Now each car carries on its bottom plate three separate and similar pick-off and release channels. Consequently, any one car may be selected to transact the business of collecting and distributing documents between some of the stations designated on the line and any one of the three pick-off and release channels on that car may be chosen for this specific business. Suppose the middle channel on car $2a$ is selected for this purpose, then from all the other stations on the line the middle channel $11a$ would be removed, then the car $2a$ would pass all said stations without taking or leaving any documents. Now, we might select car $2b$ and choose the right-side channel for the transaction of business with some of the other designated stations, then from the designated stations all the left-side channels $11a$ would be removed from the horizontal arm 11 . We now have left car $2c$ for the transaction of business with remaining stations on the line; but we must now make use of the pick-off and release channel 8 on the left side of the car. And if we want two of our conveyor-cars to collect and

distribute documents at one set of designated stations along the railway, the designated stations must be equipped accordingly, as above explained.

5 I have not undertaken to schematize the various electric circuits on the drawings, as that would have only wrought confusion in the representation of the other parts of my invention without material help, as all my circuits are definitely designated in my foregoing specification, but in Fig. 19 I have furnished an exclusive diagrammatic representation of the electric circuits involved in the automatic operation of the elevator mechanism of Fig. 6.

10 15 Thus, it can readily be seen that I have designed and developed an efficient electro-automatic document-collector-and-distributor for use in offices and sales-rooms. But in the description of my new and useful electro-automatic document-collector-and-distributor for offices and sales-rooms and other places, as set forth in the foregoing specification, it should be well understood that the specific details of the various parts of the instant embodiment of my present invention, as I have illustrated in the drawings thereof and fully described, are not to be considered as limitations in the construction of my new device; and that while keeping within the scope of my invention and claims, I may make desirable modifications in these details to facilitate quantity-production or to economize in the fabrication of the parts thereof, provided I keep within the spirit and scope of my invention and claims.

30 35 Now, having thus described the various features of my new invention, the detail construction, arrangement and combination of its parts, as well as their functions and the ways and means of assemblage, operation and application; those features and accessories of my new device for the electro-automatic document-collector-and-distributor, on which I desire Letters Patent granted to me, I have set forth specifically in the following claims.

40 45 I claim:

1. An electro-automatic document-collector-and-distributor of the kind described, consisting of an endless railway of the single-rail type suspended from an overhead structure at a certain height and adapted for carrying a plurality of electrically-operative document-conveyors, otherwise called cars; a trolley system of energized electric wires and a plurality of tappet-switches with their connected circuits, installed in predetermined places on a flexible insulation band rigidly connected with said single rail, all along the upper side thereof; a plurality of way-stations along the railway line, each station being set adjacent the desk of the station-attendant; and an elevator fixed near the attendant's desk at each of said way-stations, electrically-operative and automatically-controlled, said elevator being adapted to raise the station's pick-off and release channels high enough to exchange documents with the pick-off and release mechanism of the passing car and to bring the received documents down to the attendant's desk; and means for operating said elevator automatically as said cars move along the railway.

50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

2. An electro-automatic document-collector-and-distributor, according to claim 1, including a document-conveyor car provided with an electric motor for driving the car, including a worm and worm-gear to give the car a predetermined speed, and a pair of rubber-tired driving wheels to roll

along on the under side of said rail, and two pairs of rubber-tired bracing wheels designed to operate in service contact with the upper and side surfaces of said rail, said car having installed therein a rigid post provided on the upper portion thereof with a plurality of spring-pressed carbon brushes designed to contact the trolley wires and tappet-switches installed along said flexible, insulation band for purposes described, a plurality of pick-off and release channels fixed longitudi- 10

5 dinally on a plate fastened on the bottom of each conveyor-car, adapted to pick-off document-holders from one station-channel for delivery to another station-channel on the line, and spring-pressed latches on said pick-off and release channels adapted to retain said document-holders in passing certain stations and to release them in passing certain other stations on the line.

WILLIAM C. GIBSON.
